UNITED STATES PATENT OFFICE

HAROLD V. MCCORMICK, OF LONG BEACH, NEW YORK, ASSIGNOR, BY MESNE ASSIGNMENTS, TO WESTINGHOUSE ELECTRIC ELEVATOR COMPANY, OF CHICAGO, ILLINOIS, A CORPORATION OF ILLINOIS

ELEVATOR CAR AND DOOR CONTROLLING MECHANISM

Application filed March 3, 1928. Serial No. 258,879.

This invention relates to improvements in mechanism designed to control the opening and closing of elevator doors and associated mechanism for controlling the movement of 5 the car in the shaftway.

It is an object of the invention to provide a locking means for each door of the shaftway, a door-controlled disabling means whereby the car-operating mechanism may be rendered impotent, and means carried partly by 10 the car and partly at the various landings whereby each door may be operatively connected with its own locking means when the car is within a predetermined distance above 15 or below the level of the corresponding landing, and through which the locking means may be rendered ineffective by an opening movement of the door.

In the preferred form of the invention 20 herein disclosed, the interrelated door and car controlling mechanism is indicated as being applied to an electrically-operated elevator, and the specific type of disabling means selected for purposes of illustration is in the 25 nature of a cut-out switch in the leads which connect the usual controller with the motor-operating switches.

The invention in its preferred form is also 30 illustrated as being applied to an elevator installation comprising double doors operated by the usual self-closing type of toggle opening and closing mechanisms, and the part of the operating mechanism for the locking and disabling devices at each landing 35 is indicated as being connected with the door-operating mechanism in such manner that the release of the door may be effected as a result of an initial opening movement of 40 the operating mechanism, thus permitting the movement to be continued until the door has been opened to the desired degree. As 45 herein illustrated, the operating connection by which the disabling device is rendered ineffective is also connected with the door-opening mechanism in such manner as to cause the car-operating mechanism to be rendered impotent during the initial opening 50 movement of the door, thus making it impossible to move the car from the landing by

operating the controller until the door has been closed.

The operating connections between the elevator doors and their locking means and between the elevator doors and the disabling 55 means for the car-operating mechanism, being mounted partly on the car and partly at each landing, are separated on movement of the car from a landing, thereby rendering such connecting mechanism ineffective whenever the car is in motion between two landings. The use of the door, and, more particularly, the door-operating mechanism, in the preferred form herein disclosed, as the primary operating element of the operating 60 connections with the lock-releasing and disabling mechanisms makes it possible to effect a release of the locking means and a disabling 65 of the car-operating mechanism when the car is at a landing without burdening the operator of the car with any duty other than that which is necessary to stop the car and open the door in the usual manner. It is not at all essential that the disabling means whereby the car-operating mechanism may 70 be rendered impotent when the door is opened be carried by the car. Such disabling means 75 may be associated with some controlling element of the car-operating mechanism in any appropriate manner. All that is important 80 from the standpoint of the present invention is that the disabling means shall be operatively connected with the doors at the various landings so as to be rendered effective during 85 the initial opening movement of any door.

In the preferred form of the invention herein disclosed:—

Figure 1 is a view of a double door and its operating mechanism at a landing of an elevator shaftway, as viewed from within the 90 shaftway.

Fig. 2 is a view in detail, drawn to a larger scale, illustrating a disabling device for the car-operating mechanism, a locking device for the door at a landing, and their associated 95 operating mechanism, the direction of view of Fig. 2 being taken at right angles to that of Fig. 1.

Fig. 3 is a view of the locking device illustrated in Fig. 2 and a part of its operating 100

mechanism, the parts being shown as having been moved to their door-releasing relation.

Fig. 4 is a conventional view of one form of car-controller and an associated cut-out switch adapted for use as a disabling device for the car-operating mechanism.

In Figs. 1 and 2 is illustrated a double door 20, comprising door elements 21, 22 mounted for sliding movement so as to open and close a door opening at a landing 23 of an elevator shaftway.

As an appropriate means whereby the door sections 21 and 22 may be opened and closed, there is disclosed in Fig. 1 a self-closing operating mechanism of a well-known type comprising a bar 24 pivotally connected to the door section 21 at 25, a lever 26 pivotally connected to the door section 22 at 27, and a second lever 28 pivotally connected to a fixed part of the shaftway as at 29. The bar 24 may be pivotally connected to the arm 30 of the lever 26 as at 31, and the lever 28 may be pivotally connected to the arm 32 of the lever 26 as at 33, so as to form a toggle device adapted to prevent the opening of the door other than by the use of the mechanism when the pivotal connections of the various elements of the device are in alignment, as indicated in Fig. 1 of the drawings.

Any suitable means may be provided to serve as a stop and thus maintain the parts of the operating mechanism in normal position. Such stop may comprise a projection 34 carried by the arm 32 of the lever 26 in position to enter a slot 35 in an extended end portion 36 of the lever 28. The arm 30 may be provided with the usual handle 37 whereby the toggle may be broken and the mechanism operated to open the doors.

The above-described door-operating mechanism may be rendered self-closing by means of a spring (not shown), which may be enclosed within a cylinder 38 pivotally connected at one end to a fixed part of the shaftway as at 39 and having a piston (not shown) enclosed within the cylinder and connected by means of a piston rod 40 with the lever 28 as at 41, the spring being confined between the piston and the end of the cylinder in such manner as to be caused to store energy on the opening of the door and serve as a means of automatically closing the door when free. If desired, the piston and cylinder may be so related as to serve as a buffer in a well-known manner, thereby gently bringing the doors to rest at the end of the closing movement.

Mechanisms of the character thus far described are well known in the prior art and form no part of the invention herein sought to be protected, other than as a part of the combination herein claimed.

The invention, which will now be described, contemplates the provision of means whereby the door at any landing may be locked except when the car is within a predetermined

distance above or below the landing, so that at other times it will be impossible to effectively open the door by the operation of the usual door-opening mechanism.

In the specific form of the invention herein illustrated, the door-locking device (see Fig. 2) comprises a pawl 42 pivotally connected at 43 to one arm of a bell-crank 44, said bell-crank being in turn pivotally connected as at 45 to a bracket 46 secured to some fixed part 70 of the elevator shaftway. The other arm of the bell-crank 44 may be connected by means of a link 47 with one end of a connecting rod 48, the other end of which (see Fig. 1) may be pivotally connected as at 49 with some part 80 of the lever 28 such as to cause the rod 48 to be moved upwardly on the initial opening movement of the door-opening mechanism, thereby causing the bell-crank 44 (Fig. 2) to be rocked in a clockwise direction.

The above-mentioned pawl 42 and associated parts thus far described cooperate with a stop 50, which may comprise a fixed part of the bracket 46, to limit the movement of the pawl and such connected parts and thus prevent any appreciable opening movement of the door unless the operation of the mechanism is modified by mechanism carried by the car, which will now be described. This mechanism may comprise a cam-like shoe 51 supported by parallel arms 52, 53, said arms being pivotally connected to the shoe as at 54, 55, and pivotally connected as at 56, 57, to a bracket 58 mounted on the car body 59.

The pivotal mounting 57 of the arm 53 may comprise a pintle or shaft having a second arm 60 fixed thereto, said arm 60 being connected by means of a rod 61 with an arm 62 adapted to operate a disabling device for the car-operating mechanism, said device being represented generally by the reference character 63.

Journaled in an arm 64 forming part of the pawl 42 is a roller 65 adapted to cooperate with the vertical surface 66 of the shoe 51, which is so located as to be closely adjacent to the roller when the car is at the landing. The shoe 51, arm 64 and roller 65 cooperate to complete the operating mechanism for the locking pawl 42 when the car is at the landing, in a manner to be hereinafter described, and the shoe 51 and connected parts cooperate with the pawl 42 and parts connected therewith to complete an operating connection from the door to the disabling device 63 when the car is at the landing.

The foregoing description should make it clear that, if the car is at a distance above or below the landing such as to remove the shoe from its cooperative relation with the arm 64 and roller 65, an attempt to open the door by means of the door-operating mechanism disclosed in Fig. 1 will be unsuccessful, since the initial movement of the toggle mechanism will cause the bell-crank 44 to be

rotated slightly in a clockwise direction such as will cause the pawl 42 to engage the stop 50 and prevent any effective opening movement of the door. On the other hand, if the car is located within a distance above or below the landing determined by the length of the surface 66 of the shoe, the initial opening movement of the toggle mechanism of Fig. 1 will cause the roller 65 (Fig. 2) to be brought into contact with the surface 66 of the shoe 51, after which, due to the resistance offered by the shoe and its connected parts, further clockwise movement of the bell-crank 44 will cause the pawl 42 to be slightly rotated about its pivotal connection with said bell-crank to the position indicated in Fig. 3. Under such conditions it will be apparent that no resistance will be offered to the continued movement of the toggle mechanism (Fig. 1) by which the door may be freely opened to any desired extent. This continued movement of the door-opening mechanism will cause the roller 65 of the pawl 42 to be brought into contact with the adjacent part of the bell-crank 44, after which the bell-crank and the pawl will be effective as a unit to drive the shoe 51 towards the right as illustrated in Fig. 2, thus moving the shoe and connected parts to the positions indicated in broken lines in said figure, this being the position in which the disabling device 63 renders the car-operating mechanism impotent and thereby makes it impossible to cause the car to leave the landing until the door has been closed. As the door is closed, the shoe 51 may be caused to follow the return movement of the roller 65 during the counter-clockwise rotation of the bell-crank 44 in which it is mounted, this return movement being effected, if desired, by a spring (not shown) or any other appropriate means.

The shoe 51 may be provided with surfaces 67, 68, which cooperate with the surface 66 to form a cam-like device adapted to gently engage the roller 65 and prevent destruction of the parts of the mechanism should the car be caused to approach a landing at which the locking mechanism, for some exceptional reason, has been manually released and the door left open, thus placing the parts of the mechanism in abnormal relationship.

Fig. 4 is a conventional representation of an electric controller 69, comprising a conductive segment 70 which may be moved by an operating arm 71 and thereby caused to close either of two circuits, one of which normally conditions the operating mechanism of the car for ascent and the other of which conditions it for descent. By movement of the operating arm 71 in a clockwise direction the circuit may be closed at the controller from conductor 72 to conductor 73 at electric contacts 74, and unless this circuit is opened at another point by the disabling means, hereinafter to be described, the car

will be caused to move in one direction by its operating mechanism. On movement of the arm 71 in a counter-clockwise direction, conductor 75 will be connected with conductor 76 at the contacts 77, and unless the circuit is opened by the disabling means the car will be moved in the opposite direction.

The disabling device 63 whereby the controller 69 and other parts of the car-operating mechanism may be rendered impotent by the door-operating mechanism disclosed in Fig. 1, through the intermediate mechanism disclosed in Fig. 2, as herein disclosed, comprises a double pole switch 78 consisting of connectors 79, 80, pivotally mounted as 81, 82, by which, when in closed position, conductor 73 may be connected with conductor 83, and by which conductor 76 may be connected with conductor 84. These connectors 79, 80 may be mutually connected by 85 an insulated bar 85 having a pin-and-slot connection or other appropriate coupling with one arm of a lever 86 pivotally mounted within the housing at 87, the other arm 62 of said lever being pivotally connected as at 88 with the connecting rod 61 (see Fig. 2).

When the door at the landing is closed and all parts of the mechanism are in their normal positions as indicated in full lines in Figs. 1 and 2, the connecting elements of the disabling device will be in their circuit-closing positions as indicated in broken lines in Fig. 4, thus permitting the controller of the car-operating mechanism to function in its normal manner and serve as a means whereby the car may be caused to move either up or down in the elevator shaft at will. The effect of the force of gravity on the shoe 51 and arms 52, 53, is such as to tend to maintain the parts of the mechanism in the positions indicated in full lines in Fig. 2 and in broken lines in Fig. 4, and to return them to such positions when removed therefrom. If desired, a spring, not shown, may be provided to render such return of the parts to normal positions more certain. On the other hand, if the car is at a landing and an initial movement is imparted to the door-operating mechanism of Fig. 1, the parts of the disabling device will be moved through the intermediate operating mechanism disclosed in Fig. 2 to the position indicated in full lines in Fig. 4, thereby opening the leads 72, 73, 83, and 75, 76, 84 from the controller to the motor-controlling switches, thus rendering the car-operating mechanism impotent.

From the foregoing description it will be apparent that the lock-releasing device for the door, when constructed in accordance with the improved form of the invention herein disclosed for purposes of illustration, comprises relatively movable parts of an operating connection between the door-opening toggle mechanism and the means for disabling the car-operating mechanism. Such

relatively movable parts include the pawl 42 and the bell-crank 44, which are caused to release the door from its locking means whenever the roller 65 meets with the obstruction offered by the shoe 51 if the car is at the landing. The separation of the lock-releasing mechanism into parts one of which is mounted on the car and the other of which is mounted at the landing results in a separation of the parts of the mechanism whenever the car is moved away from the landing, thereby preventing an effective operation of the lock-releasing mechanism if the car is in motion between two landings.

15 The invention is not intended to be limited to the preferred form herein disclosed for purposes of illustration, but should be regarded as including modifications and variations thereof within the scope of the appended claims.

What is claimed is:

1. The combination with an elevator car, the operating mechanism whereby it may be moved in its shaftway, a door at a landing of the shaftway and an operating mechanism for the door, of a locking device for the door, a disabling device for the car-operating mechanism having an operating connection with the door, and a lock-releasing device whereby the opening of the door may be made dependent upon the position of the car in the shaftway, the lock-releasing device comprising mutually cooperative parts mounted respectively on the car and at the landing and having an operating connection with the door-operating mechanism, the parts being so related as to be separated and thereby rendered ineffective except when the car is within a predetermined distance above or below the landing, at which time the locking device may be rendered ineffective by the releasing device as a result of an initial door-opening movement of the door-operating mechanism, and the car-operating mechanism may be rendered ineffective by the disabling device as a result of an opening movement of the door.

2. The combination with an elevator car, the operating mechanism whereby it may be moved in its shaftway, a door at a landing of the shaftway and an operating mechanism for the door, of a locking device for the door, a disabling device for the car-operating mechanism having an operating connection with the door, and a lock-releasing device whereby the opening of the door may be made dependent upon the position of the car in the shaftway, the lock-releasing and disabling devices comprising mutually cooperative parts mounted respectively on the car and at the landing, and the releasing device having an operating connection with the door-operating mechanism, the parts being so related as to be separated and thereby rendered ineffective except when the car is with-

in a predetermined distance above or below the landing, at which time the locking device may be rendered ineffective by the releasing device as a result of an initial door-opening movement of the door-operating mechanism, and the car-operating mechanism may be rendered ineffective by the disabling device as a result of an opening movement of the door.

3. The combination with an elevator car, the operating mechanism whereby it may be moved in its shaftway, a door at a landing of the shaftway and an operating mechanism for the door, of a locking device for the door, a disabling device for the car-operating mechanism, and a lock-releasing device whereby the effective opening of the door may be made dependent upon the position of the car in the shaftway, the lock-releasing and disabling devices being operatively connected with the door-operating mechanism, the releasing device comprising mutually cooperative parts mounted respectively on the car and at the landing, the parts being so related as to be separated and thereby rendered ineffective except when the car is within a predetermined distance above or below the landing, at which time the locking device may be rendered ineffective by the releasing device and the car-operating mechanism may be rendered ineffective by the disabling device as a result of an opening movement of the door-operating mechanism.

4. The combination with an elevator car, the operating mechanism whereby it may be moved in its shaftway, a door at a landing of the shaftway and an operating mechanism for the door, of a locking device for the door, a disabling device for the car-operating mechanism, and a lock-releasing device whereby the effective opening of the door may be made dependent upon the position of the car in the shaftway, the lock-releasing and disabling devices comprising mutually cooperative parts mounted respectively on the car and at the landing, each having an operating connection with the door-operating mechanism, the parts being so related as to be separated and thereby rendered ineffective except when the car is within a predetermined distance above or below the landing, at which time the locking device may be rendered ineffective by the releasing device and the car-operating mechanism may be rendered ineffective by the disabling device as a result of an opening movement of the door-operating mechanism.

5. The combination with an elevator car, the operating mechanism whereby it may be moved in its shaftway and a door at a landing of said shaftway, of a locking device for the door, a disabling device for the car-operating mechanism, and an operating connection between the door and the disabling device including relatively movable parts adapt-

ed to serve as a lock-releasing device, whereby the effective opening of the door may be made dependent upon the position of the car in the shaftway, the operating connection comprising mutually cooperative parts, one mounted on the car and the other mounted at the landing, the parts being so related as to be separated and thereby render the operating connection ineffective except when the car is
5 within a predetermined distance above or below the landing, at which time the locking device may be rendered ineffective by the releasing device as a result of an initial opening movement of the door and the car-operating mechanism rendered ineffective by the disabling device as a result of a further opening movement of the door.

6. The combination with an elevator car, the operating mechanism whereby it may be
20 moved in its shaftway, a door at a landing of said shaftway and an operating mechanism for the door, of a locking device for the door, a disabling device for the car-operating mechanism, and an operating connection between
25 the door-operating mechanism and the disabling device including relatively movable parts adapted to serve as a lock-releasing device, whereby the effective opening of the door may be made dependent upon the position of the car in the shaftway, the operating connection comprising mutually cooperative parts, one mounted on the car and the other mounted at the landing, the parts being so related as to be separated and thereby render
30 the operating connection ineffective except when the car is within a predetermined distance above or below the landing, at which time the locking device may be rendered ineffective by the releasing device as a result of an initial opening movement of the door-operating mechanism, and the car-operating mechanism rendered ineffective by the disabling device as a result of a further opening movement of the door-operating mechanism.

45 In witness whereof, I have hereunto signed my name.

HAROLD V. McCORMICK.
